Patented Sept. 12, 1922.

UNITED STATES PATENT OFFICE.

RUFUS K. STARKEY, OF HENNESSEY, OKLAHOMA.

BUSHING REMOVER.

Application filed May 7, 1921. Serial No. 467,606.

To all whom it may concern:

Be it known that I, RUFUS K. STARKEY, a citizen of the United States, residing at Hennessey, in the county of Kingfisher and State of Oklahoma, have invented certain new and useful Improvements in Bushing Removers, of which the following is a specification, reference being had to the accompanying drawings.

10 This invention relates to bushing removers and more particularly to a device for removing or replacing bushings in one of a plurality of alined openings.

An important object of the invention is 15 to provide a device of this character which has means engaging in one of a plurality of alined openings for alining a shaft with the remaining openings, the shaft being provided upon opposite ends thereof with means 20 for removing or replacing a bushing and means whereby the shaft may be shifted longitudinally in either direction.

A further object of the invention is to provide a device of this character which may be 25 readily employed for removing the rear bushing of automobile engine cam shafts, and more particularly the rear cam shaft bushing of the engine at present employed in a Ford automobile and Fordson tractor.

30 Other objects and advantages of the invention will become apparent throughout the course of the following description.

In the accompanying drawings, wherein for the purpose of illustration is shown a 35 preferred embodiment of my invention and wherein like reference characters designate like parts throughout:

Figure 1 is a side elevation partially in section, showing a device constructed in accordance with my invention in use for removing a bushing;

Figure 2 is a similar view showing the device employed for replacing a bushing;

Figure 3 is a detail view partially in section of the operating shaft; and

Figures 4 and 5 are side elevations of bushing, replacer and remover respectively.

Referring now more particularly to the drawings, the character E designates an engine frame which in the type of construction above referred to embodies openings 10, 11 and 12 adapted for the reception of the bearings of a cam shaft not herein shown. The rear bearing of the cam shaft in 50 this construction is comprised in a bushing

13 which has a driving fit with the opening 12 and which is ordinarily difficult of access.

The numeral 14 indicates a shaft of less size than the openings 10, 11 and 12, and having one end thereof screw-threaded, as at 60 14^a, the opposite end being adapted for the interchangeable reception of a bushing remover 15 and a bushing replacer 16. In the present instance the method of connecting the remover 15 and replacer 16 is shown 65 comprising an internally threaded socket 17 formed in the end of the shaft 14 and adapted for engagement with reduced threaded extensions 18 formed upon these devices.

The remover 18 has the body portion thereof tapered and formed like a tap, as indicated at 19, so that it may be readily engaged in the bushing 13 by rotating the bar. The replacer 16 is provided with a reduced extension 20 adapted to have a sliding fit in 70 the bore of the bushing 13, which reduced extension forms a shoulder 21 upon the replacer adapted to engage against the end of the bushing in a solid manner to enable the bushing to be driven into its position in the 75 opening 12.

The threaded end 14^a of the bar 14 has 80 slidably mounted thereon a member 22 having a sliding fit in one of the openings 10 or 11, preferably in the opening 10, as illustrated, to form a mounting and guide for the bar 14 so that the same may be properly alined with the opening 11 or 12 in which the bushing is to be positioned. This member 85 has a shoulder 23 abutting the wall of 90 the engine frame at the sides of the opening 10 and is adapted to be engaged by a threaded nut 24 mounted upon the screw threads 14^a of the bar 14. The extremity of the threaded portion 14^a of the bar 14 has 95 rigidly secured thereto a wrench-receiving portion 25 whereby the bar 14 may be rotated as a whole, and this wrench-receiving portion is provided with an extension 26 having a striking face 27 against which a 100 hammer may be applied to drive a bushing into position. This extension 26 may likewise be provided with an opening 28 in which a bar may be inserted to rotate the bar 14 instead of employing a wrench upon the 105 polygonal portion 25.

In the use of my device the bar 14 is inserted in one of the openings and the member 22 positioned in this opening, the bar 110 having first had applied thereto the re-

5 mover. The bar is then slid through the member 22 until the bushing remover engages in the bushing to be removed and the bar 14 rotated to firmly fix the bushing remover in said bushing. The nut 24 is then 10 rotated in engagement with the shoulder formed by the member 22, drawing the bar through the member and consequently withdrawing the bushing 13 from its seat. When 15 it is desired to replace the bushing the bar is positioned as above described, having first been provided with the bushing replacer 16, and the bushing 13 is placed upon a reduced extension 20 thereof. The bar is then moved 20 inwardly until the bushing 13 engages in the end of the opening to which it is to be applied, the nut 24 being shifted back or toward the end of the bar or away from engagement with the member 22. The bar 25 may then be forced longitudinally by blows upon the striking face 27 thereof until the bushing 13 is seated.

25 Many changes being possible in the shape, size and arrangement of the various parts hereinbefore set forth without in any manner departing from the spirit of my invention, I do not limit myself to the specific structure thereof except as hereinafter claimed.

30 What I claim is:

30 1. A device for removing or replacing bushings in one of a pair of aligned openings, comprising a member adapted to slidably engage in one of said openings and forming a guide, a bar slidably directed through said member and maintained thereby in alignment with the other of said openings, said bar being provided upon one end thereof with means whereby it may be rotated and adapted upon the other end thereof for the 35 40 interchangeable reception of a bushing re-

mover or replacer, and means mounted upon the first named end of the bar for shifting the bar longitudinally through said member.

2. A device for removing or replacing bushings in one of a pair of aligned openings, 45 comprising a member adapted to slidably engage in one of said openings and forming a guide, a bar slidably directed through said member and maintained thereby in alignment with the other of said openings, 50 said bar being provided upon one end thereof with means whereby it may be rotated and adapted upon the other end thereof for the interchangeable reception of a bushing 55 remover or replacer, and means mounted upon the first named end of the bar for shifting the bar longitudinally through said member in one direction, the first named end of the bar is likewise provided with a striking face.

60 3. A device for removing from or replacing bushings in one of a pair of aligned openings, comprising a member adapted to slidably engage in one of said openings and having means limiting its movement therethrough, a bar slidably directed through said member having one end thereof externally screw-threaded and provided with means whereby it may be rotated, a nut having threaded engagement with said end and 65 adapted to engage against said member, bushing removing and replacing implements, and coating portions formed upon the other end of the bar and said implements whereby said implements may be interchangeably secured to said end.

65 In testimony whereof I hereunto affix my signature.

RUFUS K. STARKEY.
